UNITED STATES PATENT OFFICE.

OTIS A. MYGATT, OF NEW YORK, N. Y.

DESIGN FOR A CORRUGATED PRESSED-GLASS SHADE OR REFLECTOR.

46,058.

Specification for Design.

Patented July 7, 1914.

Application filed July 1, 1909. Serial No. 505,511. Term of patent 14 years.

To all whom it may concern:

Be it known that I, OTIS A. MYGATT, residing at New York, in the county of New York and State of New York, have invented a certain new, original, and ornamental Design for Corrugated Pressed-Glass Shades or Reflectors, of which the following is a specification, reference being had therein to the accompanying drawings.

The drawing is an elevation of my design.

The design consists of a globular pressed glass shade or reflector in the form of two convex curves as shown, the outer surface

of the shade being covered with prisms arranged in planes of the axis of the shade. A horizontal section of the globe taken at any point is substantially circular.

I claim,

The ornamental design for a corrugated pressed glass shade or reflector, substantially as shown and described.

OTIS A. MYGATT.
